COMBINED FINGER RING AND WATCH

Murray Schreiber, New York, N. Y.

Application June 5, 1957, Serial No. 46,498

Term of patent 3½ years

(Cl. D45—10)

FIG.1

FIG. 2

FIG.3

FIG. 4

FIG. 5

FIG. 6

FIG. 7

Fig. 1 is a top plan view of a combined finger ring and watch, showing my new design;

Fig. 2 is a front elevational view;

Fig. 3 is a side elevational view looking from the right of Fig. 2;

Fig. 4 is a side elevational view looking from the left of Fig. 2;

Fig. 5 is a top view, showing the cover member in an open position;

Fig. 6 is a top view, showing the cover member in an open position and the watch hinged to show the rear thereof; and

Fig. 7 is a front elevational view thereof showing the cover member in an open position.

I claim:

The ornamental design for a combined finger ring and watch, substantially as shown.
